UNITED STATES PATENT OFFICE.

GEORGE C. WORTHINGTON, OF ELYRIA, OHIO.

DESIGN FOR A PLAYING-BALL.

46,783.

Specification for Design.

Patented Dec. 15, 1914.

Application filed September 14, 1914. Serial No. 861,725. Term of patent 7 years.

To all whom it may concern:

Be it known that I, GEORGE C. WORTHINGTON, a citizen of the United States, residing at Elyria, in the county of Lorain and State of Ohio, have invented a new, original, and ornamental Design for Playing-Balls, of which the following is a specification, reference being made to the accompanying drawing, forming a part thereof.

The figures are: Figure 1, is a plan view

of a playing ball embodying my design. Fig. 2, is a side elevation of Fig. one (1) tilted at an angle of forty-five degrees.

I claim:

The ornamental design for a playing ball as shown.

GEORGE C. WORTHINGTON.
